EXTRACTIVE DISTILLATION OF HYDRO-CARBONS WITH FURFURAL-WATER MIXTURES

Virgil Scarth, Bartlesville, Okla., assignor to
Phillips Petroleum Company, a corporation of
Delaware

Application December 21, 1944, Serial No. 569,244

9 Claims. (Cl. 196—13)

1

This invention relates to the extractive distillation of unsaturated hydrocarbons with furfural as the solvent, particularly to the extractive distillation of hydrocarbon streams containing aliphatic olefins and/or conjugated diolefins, especially normal butene and/or butadiene, to recover same therefrom.

It has become customary to recover unsaturated hydrocarbons particularly normal butene and/or butadiene from hydrocarbon streams containing same by extractive distillation with furfural as the solvent. Such processes are described in the patent to Hachmuth 2,386,310 and in the copending applications of Hachmuth, Ser. No. 438,844, filed April 13, 1942, and Ser. No. 454,312, filed August 10, 1942. The first-mentioned application discloses and claims the use of furfural containing several per cent of dissolved water. It will not be necessary to describe the extractive distillation process in detail since it is now quite well-known to the art. Suffice it to say that it is carried out by means of a fractional distillation column operated as an absorber into the top of which a stream of furfural is continuously fed, the rich furfural withdrawn as bottom product being passed to a stripper column where the dissolved butene and/or butadiene is driven off. The lean furfural is withdrawn from the bottom of the stripper, cooled and recycled to the absorber. Both absorber and stripper are refluxed by means of a portion of condensed overhead and both are provided with reboilers.

During the absorption and stripping operations polymer and other corrosive impurities are formed in the furfural and build up to an objectionable extent so that it is necessary to pass a sidestream of the furfural to a "re-run" unit where it is freed from the polymer and other impurities, usually by a process involving steam distillation. Methods of re-running the furfural are disclosed in the patents to Buell et al. 2,350,584, Hachmuth 2,350,609 and Hachmuth 2,372,668. The re-running operation as commercially practiced gives an overhead of steam and pure furfural which upon condensation gives a water layer and a purified furfural layer. The water layer is used to make steam employed in the steam distillation for re-running the furfural. The water layer is saturated with furfural (about 8% at 120° F.). This dissolved furfural has in the past been saved by using the water layer to make the process steam used in the re-run operation. However, in making steam by this method the tubes in the steam generator have been difficult to keep clean because furfural dissolved in the water becomes polymerized and deposits on the tubes.

In the extractive distillation of unsaturated hydrocarbons with furfural containing dissolved water as a solvent, water is volatilized and carried overhead in admixture with the hydrocarbon

vapor. Upon condensation of the overhead vapors this water is condensed and forms a separate water layer in the reflux accumulator. This occurs in connection with both the absorber and the stripper. Conventional practice in the past has been to add the water thus stripped from the furfural back to the furfural fed to the absorber, as makeup water.

It has been commonly observed that even when the furfural in the extractive distillation system is re-run at a rate such as to re-run all the furfural in the system every two or three days, the furfural in the main system, i. e., the extractive distillation system proper, becomes corrosive. This corrosiveness is objectionable because the equipment such as the expensive bubble tray absorber and stripper is eaten away at an excessive rate. The causes underlying the corrosivity of the furfural are not understood at present. Some investigators believe that the corrosiveness results from the decomposition and polymerization of the furfural under the particular conditions prevailing in the absorber and stripper with the formation of organic acids and furfural polymer which are believed to be corrosive of carbon steel. It is thought that other factors are involved since corrosion is not always directly proportional to acid content of the furfural, especially at acid levels above 0.06 per cent by weight measured as acetic acid. For example, while corrosion is never serious at acidities below 0.04 per cent, at acidities between 0.04 and 0.06 per cent serious corrosion may or may not occur depending upon factors unknown at present; and at acidities above 0.06 per cent serious corrosion is usually encountered and in some cases it is so excessive that the plant could be continued in operation for only a short period of time before it would be eaten away to an unsafe point. It can be definitely stated that the problem of corrosion by furfural is most difficult to solve at the present state of the art. In fact, so far as I am aware, no completely satisfactory methods of completely eliminating the problem of corrosion by furfural have been developed.

Another disadvantage of present methods of operation is that the furfural becomes corrosive in the extractive distillation system and causes corrosion in the system before it can reach the re-run unit since it is necessary that the furfural re-run rate be kept at a minimum because losses of furfural in the re-run unit are high.

The principal object of the present invention is to provide an improved process of carrying out the extractive distillation of unsaturated hydrocarbons with furfural as the solvent. Another object is to provide such a process for the recovery of normal butene and/or butadiene. Another object is to provide such a process wherein corrosion of the extractive distillation system is

substantially reduced. Another object is to provide such a process wherein the steam vaporizer or generator used for generating process steam for use in the furfural re-run unit is caused to operate much more satisfactorily than when using present methods of operation. Another object is to eliminate polymerization of furfural in the process steam generator with resulting deposition of objectionable material on the tubes of the vaporizer. Another object is to provide a method which accomplishes the foregoing aims and objects in a simple and economical manner and which can be applied to existing furfural extractive distillation systems, heretofore operated in the conventional manner, with a minimum of trouble and changes. Many other objects of the present invention will be apparent from the following description to those skilled in the art.

The accompanying drawing portrays diagrammatically an arrangement of equipment for carrying out the present invention.

While in the drawing I have shown only a single absorber and a single stripper it will be obvious that any number of these may be employed. For example, in the manufacture of butadiene by the two-stage catalytic dehydrogenation of normal butane it is now conventional to provide a furfural extractive distillation system for recovering unsaturated components from each catalytic effluent, the furfural extraction provided between stages serving to separate butene-2 from normal butane and the furfural extraction operating on the second stage effluent serving to separate butadiene and butene-2 from other C₄ hydrocarbons; it is customary to cool and combine the lean furfural streams leaving the bottoms of both strippers and to pass the resulting composite recycle stream to a common furfural surge or storage tank from which furfural is pumped to the absorbers; it is also conventional to employ a single furfural re-run unit to which a sidestream of the lean furfural is fed, the re-run furfural being merged with the recycle furfural passed to surge.

In accordance with the present invention the water removed overhead in the absorber and stripper units of the extractive distillation system forming a separate layer in the overhead accumulator associated with the absorber and stripper is separately withdrawn and is employed as the source of steam employed in the re-running of the furfural.

I have discovered that the water which goes overhead in the absorber and stripper units is corrosive. This water contains up to about 1% of dissolved furfural (which is vaporized in the absorber and stripper in spite of measures taken to prevent loss of furfural in this manner) and practically no inorganic chemicals. As explained above, past practice has been to add this water as makeup to the lean furfural fed to the absorber in order to keep the level of dissolved water in the furfural substantially constant. The water recovered from the overhead was saved and added back to the extractive distillation system in order to conserve the furfural dissolved in the water since furfural is very expensive and because at times it has appeared that the available supply of furfural might be insufficient for the butadiene program.

The nature of the corrosive material present in the water phase which appears in the condensate accumulators associated with the furfural absorber and stripper is not known nor is it known how it forms or why it goes overhead with the water and hydrocarbon. The corrosive material

probably forms in the absorber and stripper and is probably stripped from the furfural in the absorber and stripper. It is believed that the corrosive material is removed as a vapor at the temperatures maintained in the absorber and stripper and that the concentration of this foreign material builds up in the water if the water is continually returned to the furfural as make-up water. When this water is added to non-corrosive furfural it becomes corrosive. Thus, when the water phase is added back to the system in accordance with existing practice the corrosive material is returned thereto.

I have discovered that this difficulty can be overcome by employing the water layer as a source of process steam for the re-run operation. The water may be fed to the conventional steam generator used for making the process steam and thereby vaporized, the resulting steam being injected into the re-run unit for steam distilling, the furfural being re-run. Alternatively the water may be introduced as liquid water into the re-run unit and vaporized therein by extraneous heat.

By passing the water layer, either as steam or liquid, to the re-run unit in accordance with the present invention, the corrosive substance, whatever it is, removed from the water. At the same time the furfural content of the water layer is conserved.

While it is preferred to effect the distillation of the water in the re-run unit in the manner discussed above and described in detail below, the distillation may be conducted in other ways: for example, the water layer may be passed to a distillation unit and there distilled at atmospheric pressure whereby the corrosive material is caused to remain in the residue or kettle product. Such a plain distillation is ordinarily carried out in such manner that not over 95% of the water appears in the distillate since upon concentration of the corrosive material beyond this point there is danger of driving corrosive material overhead. The distillation should not be carried beyond the point where the kettle temperature exceeds the boiling point of water by one degree Fahrenheit.

The re-run operation may be carried out in the manner shown in Buell et al. 2,350,584, except that (1) the water layer formed by condensing the furfural-water overhead vapors is not passed to the steam vaporizer of the re-run unit but instead is passed to the extractive distillation system, for example, being introduced as makeup to the lean furfural fed to the absorber in such amount as to maintain the content of dissolved water in the furfural solvent in the extractive distillation system at a substantially constant predetermined level, and (2) the steam vaporizer of the re-run unit is fed with the water recovered as a separate phase in the condensate accumulator employed for collecting the condensed overhead vapors from the absorber and stripper. The re-running operation is carried out at pressures ranging from atmospheric to moderately superatmospheric, say up to about 30 pounds gage, in order to minimize additional polymerization in the re-run step. Where straight distillation of the water phase in a unit apart from the re-run is practiced, pressures of the same order are employed.

The water distillate resulting from distillation of the corrosive water phase in accordance with the present invention may be introduced to the extractive distillation system, generally by addition as makeup water to the lean furfural fed to an absorber unit in the system. Where, in ac-

cordance with the preferred practice of the invention, the corrosive water phase is passed to the re-run unit and there vaporized to form steam, the water thereby vaporized ultimately appears as the water layer in the accumulator for the condensed overhead vapors of the re-run unit. This water layer is free of corrosive material but is saturated with furfural and is preferably added to the lean furfural fed to the absorber in such proportions as to impart the proper water level thereto. In this way the dissolved furfural content of the water layer is saved.

Where a re-run unit of the type shown in Fig. 2 of Buell et al. 2,350,584, is employed, I may introduce a portion of the corrosive water phase in liquid form directly into one of the evaporators which are placed in series ahead of the final stripper into which process steam from the vaporizer is introduced. The evaporators are at such a high temperature that such liquid water is immediately flashed into steam therein. This procedure gives an exceptionally pure re-run furfural, practically water-white in color, and in addition aids in keeping the temperature in the evaporators at a suitably low level. It is preferred to inject the liquid water into the second evaporator of the series, although it might be introduced into the first evaporator. When the water is fed into the second evaporator in this manner it is vaporized therein and passes in vapor phase through the first evaporator to appear in the condensate settler.

The corrosive material contained in the corrosive water phase introduced to the re-run unit in accordance with the present invention is eliminated along with the polymer from the final stripper column in the re-run unit. Likewise, where the water phase is subjected to simple distillation to remove non-corrosive water as an overhead product the residue containing the corrosive material is withdrawn from the still or column and discarded.

My invention takes advantage of two unexpected discoveries; first, that corrosive material is volatile and removed overhead from the furfural absorber and stripper under the conditions of operation and concentrated in the water layer separating in the overhead accumulators, and, second, that this corrosive material can be removed from the water by distillation preferably by vaporizing the water phase and injecting the resulting steam into the re-run unit and/or injecting at least a portion of the water phase directly into the re-run unit and thereby vaporizing and distilling it in intimate contact with the furfural.

Referring to the accompanying drawing, a C₄ hydrocarbon feed containing an unsaturated hydrocarbon, which it is desired to recover, enters absorber 1 via line 2. Furfural is continuously injected into the top of absorber 1 via line 3. The furfural, enriched in unsaturated hydrocarbon, is withdrawn via line 4. The overhead from column 1 is condensed in condenser 5 and fed to accumulator 6 where it is allowed to separate into two layers, the lower layer being a water layer and the upper layer being composed of residual C₄ hydrocarbons. A portion of the upper layer is fed as reflux via line 7 to the top of column 1, entering at a point slightly above the point of furfural entry. The balance of the hydrocarbon layer is withdrawn via line 8.

The rich furfural is fed via line 4 to stripper 9 where the unsaturated hydrocarbon dissolved therein is driven off in the usual way, the lean

furfural being withdrawn via line 10. The overhead is condensed and the condensate accumulated in tank 11 where it is allowed to separate into two layers. The upper hydrocarbon layer is, in part, fed as reflux via line 12 to the top of column 9, while the balance is withdrawn as product via line 13.

The lean furfural passes via line 10 through cooler 14 where it is cooled to a point suitable for reintroduction into the absorber 1 and is then recycled via line 15 to surge tank 16 whence it is fed into absorber 1.

A side stream of the cooled furfural is passed via line 17 to the re-run unit which is constructed in the manner described in Fig. 2 of Buell et al. 2,350,584. The re-run unit comprises two evaporators 18 and 19 arranged in series followed by a stripper 20. The furfural is introduced into the first evaporator, the residue passing into the second evaporator and the residue from the second evaporator passing into the stripper 20. Live steam generated in vaporizer 21 is injected into the bottom of stripper 20. The vapors of furfural and water leaving unit 20 are fed into the bottom of evaporator 19 and the vaporized furfural and water leaving unit 19 are fed into the bottom of evaporator 18. The vapors of the purified furfural and water pass overhead from evaporator 18 via line 22, are condensed in condenser 23 and accumulated in separator 24 where layer formation takes place. The polymer in admixture with water and sufficient furfural to render it fluid is removed from the stripper 20 and discarded. The purified furfural layer accumulated in separator 24 is withdrawn and passed via line 25 into admixture with the main recycle stream going to surge or storage 16.

In accordance with the present invention, the water layers separating in accumulators 6 and 11 are withdrawn via lines 26 and 27, merged and passed via line 28 as the water used to generate process steam for the re-run unit in steam generator 21.

Further, in accordance with the present invention, the water layer separating in unit 24 is passed via line 29 to water surge 30 and thence as make-up water to the furfural recycle passed to absorber 1.

If desired, a portion of the corrosive water flowing in line 28 may be passed via line 31 and injected directly in liquid form into the bottom of evaporator 19. A portion of this corrosive water might also be injected directly in liquid form into the bottom of evaporator 18, although this would almost never be found desirable. In very rare instances all of the water in line 28 might be passed via line 31 to be injected into the bottom of evaporator 19, in which case a separate source of water would have to be provided for making process steam for the re-run unit in steam generator 21.

Example

In the manufacture of butadiene by two-stage dehydrogenation of normal butane, an absorber and stripper were used between the first and second stage for separating butene-2 from normal butane and another absorber and stripper were employed to separate butadiene and butene-2 from a C₄ fraction of the second stage effluent. The system was as shown in the drawing except that there were two absorber-stripper combinations. Furfural was fed continuously into the absorbers at the rate of 260,000 gal./hr. entering both absorbers. The furfural containing 6% of

water by weight based on the weight of furfural and water. Stripped furfural from both strippers was cooled to 120-130° F. and the major part of the cooled product was passed via line 15 to furfural surge 16. The total volume of furfural in the entire system was 225,000 gal. Furfural was passed to the re-run unit at the rate of 3500 gal./hr.

Water appeared as a separate phase in the condensate accumulators provided for the overhead products of the absorbers and strippers at an average rate of 200 gal./hr. This water was, in accordance with the present invention, withdrawn and passed at an average rate of 200 gal./hr. via line 28 to steam generator 21 associated with the re-run unit. In the unit 21 this water was vaporized and the resulting vapors employed as process steam in the re-run unit in the manner shown in the drawing.

The overhead from evaporator 18, composed of purified furfural vapors and steam free from corrosive substances, was fed via line 22 to condenser 23 where it was totally condensed. The condensate was passed to separator 24 and allowed to separate into two layers therein. The purified furfural layer was withdrawn via line 25 and fed to the furfural surge 16. The water layer appearing in unit 24 was composed of essentially pure water saturated with furfural and was withdrawn via line 29 and employed as make-up water for the lean furfural fed to the absorbers. At times the amount of water from this source was insufficient and it was necessary to add small amounts of water from another source.

By operating in accordance with this example, corrosion in the extractive distillation systems was greatly reduced. Furthermore, difficulty which had previously been encountered due to fouling of the tubes in steam generator 21 was eliminated.

The process of the present invention gives rise to numerous advantages over prior practice. Among these the following may be enumerated: the principal advantage of the present invention is that the corrosive material is removed from the water going overhead in the absorbers and strippers before this water is returned to the main system. Another advantage is that the water used for making process steam contains less furfural and therefore fouling of the tubes in the steam generating unit is prevented. Another advantage is that the water used for making process steam contains less furfural than was the case where the prior method of using the water layer derived from the re-run overhead was employed as the source of water; therefore the furfural is stripped from the polymers faster in the re-run unit and less furfural is polymerized in this part of the process. Another advantage is that less furfural is polymerized in the steam generating unit. Another advantage is that less steam is required for stripping furfural from the polymers in the re-run unit. Another advantage is that the process of the present invention is carried out in a simple and economical manner and that no additional equipment is required to adopt the process of the present invention to existing plants, the only change required is a change in the piping layout of the plant. Many other advantages of the present invention will be apparent to those skilled in the art in the light of this disclosure.

I claim:

1. In a process for the recovery of unsaturated hydrocarbons from admixture with less saturated

hydrocarbons by extractive distillation with furfural containing dissolved water as selective solvent wherein water is volatilized and passes overhead together with hydrocarbons from furfural absorbing and furfural stripping steps, the total overhead from each of said steps is condensed and is separated into two layers, namely, a hydrocarbon layer and an aqueous layer containing corrosive impurities; while a portion of stripped furfural is withdrawn from said furfural stripping step and such withdrawn furfural is steam distilled to remove polymers and other impurities therefrom prior to returning said furfural to said furfural absorption step; that improvement which comprises eliminating corrosive impurities by withdrawing said aqueous layers containing corrosive impurities and using them as the source of steam for steam distilling said stripped furfural.

2. In a process for the recovery of unsaturated hydrocarbons from admixture with less saturated hydrocarbons by extractive distillation with furfural containing dissolved water as selective solvent wherein water is volatilized and passes overhead together with hydrocarbons from furfural absorbing and furfural stripping steps, the total overhead from each of said steps is condensed and is separated into two layers, namely, a hydrocarbon layer and an aqueous layer containing corrosive impurities; while a portion of stripped furfural is withdrawn from said furfural stripping step and such withdrawn furfural is steam distilled to remove polymers and other impurities therefrom prior to returning said furfural to said furfural absorption step; that improvement which comprises eliminating corrosive impurities and decreasing loss of water and furfural from the system by withdrawing said aqueous layers containing corrosive impurities, employing them as the source of steam for steam distilling said stripped furfural, and returning the water distilled overhead with such furfural to the extractive distillation system.

3. In a process for the recovery of unsaturated hydrocarbons from admixture with less saturated hydrocarbons by extractive distillation with furfural containing dissolved water as selective solvent wherein water is volatilized and passes overhead together with hydrocarbons from furfural absorbing and furfural stripping steps, the total overhead from each of said steps is condensed and is separated into two layers, namely, a hydrocarbon layer and an aqueous layer containing corrosive impurities; while a portion of stripped furfural is withdrawn from said furfural stripping step and such withdrawn furfural is steam distilled to remove polymers and other impurities therefrom prior to returning said furfural to said furfural absorption step; that improvement which comprises eliminating corrosive impurities and decreasing loss of water and furfural from the system by withdrawing said aqueous layers containing corrosive impurities, employing them as the source of steam for steam distilling said stripped furfural, condensing overhead steam and furfural vapors from said steam distillation of furfural, separating the resulting condensate into aqueous and furfural layers and introducing said last-mentioned aqueous layer as make-up water into furfural fed to said furfural extraction step.

4. In a process for the recovery of unsaturated hydrocarbons from admixture with less saturated hydrocarbons by extractive distillation with furfural containing dissolved water as selective solvent wherein water is volatilized and passes

overhead together with hydrocarbons from furfural absorbing and furfural stripping steps, the total overhead from each of said steps is condensed and is separated into two layers, namely, a hydrocarbon layer and an aqueous layer containing corrosive impurities; while a portion of stripped furfural is withdrawn from said furfural stripping step and such withdrawn furfural is steam distilled to remove polymers and other impurities therefrom prior to returning said furfural to said furfural absorption step; that improvement which comprises withdrawing said aqueous layers containing corrosive impurities, introducing them in liquid phase into said withdrawn furfural undergoing steam distillation, and withdrawing a corrosive kettle product from said steam distillation of furfural.

5. In a process for the recovery of unsaturated hydrocarbons from admixture with less saturated hydrocarbons by extractive distillation with furfural containing dissolved water as selective solvent wherein water is volatilized and passes overhead together with hydrocarbons from furfural absorbing and furfural stripping steps, the total overhead from each of said steps is condensed and is separated into two layers, namely, a hydrocarbon layer and an aqueous layer containing corrosive impurities; while a portion of stripped furfural is withdrawn from said furfural stripping step and such withdrawn furfural is steam distilled to remove polymers and other impurities therefrom prior to returning said furfural to said furfural absorption step; that improvement which comprises withdrawing said aqueous layers containing corrosive impurities, separating them by distillation into a distillate containing water and furfural free from corrosive impurities, and a corrosive kettle product; and introducing said distillate into the extractive distillation system.

6. In a process for the recovery of unsaturated hydrocarbons from admixture with less saturated hydrocarbons by extractive distillation with furfural containing dissolved water as selective solvent wherein water is volatilized and passes overhead together with hydrocarbons from furfural absorbing and furfural stripping steps, the total overhead from each of said steps is condensed and is separated into two layers, namely, a hydrocarbon layer and an aqueous layer containing corrosive impurities; while a portion of stripped furfural is withdrawn from said furfural stripping step and such withdrawn furfural is steam distilled to remove polymers and other impurities therefrom prior to returning said furfural to said furfural absorption step; that improvement which comprises withdrawing said aqueous layers containing corrosive impurities, separating them by distillation into a distillate containing water and furfural free from corrosive impurities and a corrosive kettle product; and introducing said distillate as make-up water into furfural fed to said furfural absorption step in the extractive distillation system.

7. In a process for the recovery of unsaturated hydrocarbons from admixture with less saturated hydrocarbons by extractive distillation with furfural containing dissolved water as selective solvent wherein water is volatilized and passes overhead together with hydrocarbons from furfural absorbing and furfural stripping steps, the total overhead from each of said steps is condensed and is separated into two layers, namely, a hydrocarbon layer and an aqueous layer containing corrosive impurities; while a portion of

stripped furfural is withdrawn from said furfural stripping step and such withdrawn furfural is passed to a rerun unit comprising a plurality of evaporators in series followed by a stripper in which unit said withdrawn furfural is steam distilled to free it from polymers and other impurities before being recycled to said furfural absorbing step, that improvement which comprises withdrawing said water layers containing corrosive impurities, introducing them in liquid phase into one of said evaporators in said rerun unit, withdrawing a kettle product containing corrosive impurities, condensing the water and furfural distilled overhead in said rerun unit, separating the resulting condensate into aqueous and furfural layers, and introducing said last-named aqueous layer as make-up water into furfural fed to a furfural absorption step in the extractive distillation system.

20. In a process for the recovery of unsaturated hydrocarbons from admixture with less saturated hydrocarbons by extractive distillation with furfural containing dissolved water as selective solvent wherein water is volatilized and passes overhead together with hydrocarbons from furfural absorbing and furfural stripping steps, the total overhead from each of said steps is condensed and is separated into two layers, namely, a hydrocarbon layer and an aqueous layer containing corrosive impurities; while a portion of stripped furfural is withdrawn from said furfural stripping step and such withdrawn furfural is passed to a rerun unit comprising two evaporators in series followed by a stripper in which unit said withdrawn furfural is steam distilled to free it from polymers and other impurities before being recycled to said furfural absorbing step, that improvement which comprises withdrawing said aqueous layers containing corrosive impurities, introducing them in liquid phase into the second of said evaporators, withdrawing a kettle product containing corrosive impurities, condensing the water and furfural distilled overhead in said rerun unit, separating the resulting condensate into aqueous and furfural layers, and introducing said last-named aqueous layer as make-up water into furfural fed to a furfural absorption step in the extractive distillation system.

40. In a process for the recovery of unsaturated hydrocarbons from admixture with less saturated hydrocarbons by extractive distillation with furfural containing dissolved water as selective solvent wherein water is volatilized and passes overhead together with hydrocarbons from furfural absorbing and furfural stripping steps, the total overhead from each of said steps is condensed and is separated into two layers, namely, a hydrocarbon layer and an aqueous layer containing corrosive impurities; while a portion of stripped furfural is withdrawn from said furfural stripping step and such withdrawn furfural is passed to a rerun unit comprising two evaporators in series followed by a stripper in which rerun unit said withdrawn furfural is steam distilled to free it from polymers and other impurities before being recycled to said furfural absorbing step, that improvement which comprises withdrawing said aqueous layers containing corrosive impurities, vaporizing a part of said aqueous layers, withdrawing a kettle product containing corrosive impurities from such vaporization step, introducing steam resulting from such vaporization into said stripper of said rerun unit as the source of steam for said steam distilling unit, introducing another part of said aqueous

11

layers in liquid phase into the second of said evaporators, condensing water and furfural distilled overhead in said rerun unit, separating the resulting condensate into aqueous and furfural layers, and introducing said last named aqueous layer as make-up water into furfural fed to a furfural absorption step in the extractive distillation system.
